(57) **CLAIM**

The ornamental design for a hair accessory to increase volume, as shown and described.

DESCRIPTION

FIG. 1 is a perspective view of a hair accessory to increase volume showing my new design;

FIG. 2 is a front plan view thereof;

FIG. 3 is a rear plan view thereof;

FIG. 4 is a side view thereof;

FIG. 5 is a top plan view thereof; and,

FIG. 6 is a bottom plan view thereof.

The broken line showing of environment is for illustrative purposes only and forms no part of the claimed design.
